UNITED STATES PATENT OFFICE.

PETER A. SOLEM, OF CINCINNATI, OHIO, ASSIGNOR TO J. A. FAY & EGAN COMPANY,
OF CINCINNATI, OHIO, A CORPORATION OF WEST VIRGINIA.

FEEDING DEVICE FOR WOODWORKING MACHINERY.

1,182,509.

Specification of Letters Patent. Patented May 9, 1916.

Application filed November 23, 1912. Serial No. 733,128.

To all whom it may concern:

Be it known that I, PETER A. SOLEM, a citizen of the United States, residing at Cincinnati, in the county of Hamilton and 5 State of Ohio, have invented certain new and useful Improvements in Feeding Devices for Woodworking Machinery, of which the following is a specification.

It is the object of my invention to provide novel means whereby the feed-roll or rolls in wood-working machinery have rotation imparted to them for forwardly feeding the stock across a cutter-head, or for reversing the direction of rotation of said 15 feed-roll or rolls for feeding said stock in a reverse direction for the purpose of withdrawing it from the machine; further to provide a swinging feed-roll housing with separate bearings for the feed-roll and with 20 means for adjusting said housing to elevation and for adjusting said bearings on said housing for leveling said feed-roll; further to provide novel yielding arrangement for the housing by locating a spring above the 25 housing diagonally between a relatively stationary part and the swinging housing, the connection between said spring and housing being within the arc of swing of the axis of rotation of the feed-roll on said housing; 30 further to provide novel link and cover mechanism for the feed-roll gearing; further to provide novel means for adjusting the feed-roll bearings, and, further to provide novel yielding and driving means for the 35 feed-roll, and the invention will be further readily understood from the following description and claims, and from the drawings, in which latter:

Figure 1 is a side elevation of an exemplified structure embodying my invention, the main frame of the structure being broken away. Fig. 2 is a side elevation of my improved device, the outer plates of the gear-covers being removed. Fig. 3 is a plan view of the same. Fig. 4 is a horizontal section of the same taken on the line 4—4 of Fig. 2, the reversing mechanism being removed. Fig. 5 is a bottom view, showing the adjusting mechanism for simultaneous 45 adjustment of the lower feed-rolls, the median longitudinal portion being broken away. Fig. 6 is a vertical section on the line 6—6 of Fig. 3 showing the reversing mechanism in end elevation. Fig. 7 is a plan section of the same taken on the irregular line 55

7—7 of Fig. 6. Fig. 8 is a vertical cross-section on the line 8—8 of Fig. 2, showing the means for mounting the upper feed-roll housings. Fig. 9 is a vertical cross-section on the line 9—9 of Fig. 2, showing one end 60 of the upper and lower feed-rolls and the means for adjusting the same. Fig. 10 is a cross-section on the irregular line 10—10 of Fig. 2, showing the link and gear-cover mechanism of the upper feed-roll gearing. 65 Fig. 11 is a perspective view of the gear-cover having the link-extension of the gear-cover integral therewith. Fig. 12 is an inside elevation, showing the means for supporting the bearing of the lower feed-roll. 70

Fig. 13 is a vertical section on the line 7—7 of Fig. 2, showing the means at one side of the machine, for raising and lowering the upper feed-roll housing; and, Fig. 14 is an inside side elevation of the lower 75 portion of the same.

11 represents the main frame, partly broken away, of a wood-working machine, as a planing, planing and matching, or flooring machine, or machine of similar character, embodying feeding mechanism and a cutting agency or agencies, so much of the machine only being shown as is necessary to illustrate my invention. The main frame is arranged to support a stock-supporting 80 table 12, the stock being fed across a cutting agency, shown as a rotary cutter-head 13.

14 represents a usual side guide, which is adjustable crosswise of the machine, 90 lengthwise of the feed-rolls, as by means of a T-bolt 15 adjustable in a cross T-slot 16 in the table, a nut 17 clamping the side guide in adjusted positions, the side guide extending lengthwise of the machine. 95

I have illustrated my invention as applied to a feeding device having a pair of front feed-rolls and a pair of rear feed-rolls, although it is obvious that, in employing portions of my invention, one pair 100 of feed-rolls may be employed.

18, 19, represent lower feed-rolls, and 20, 21 represent upper feed-rolls. The upper feed-rolls are respectively mounted in housings 22, 23, the housing 22 having bearings 105 24 pivoted on sleeves 25, 26, and the housing 23 having bearings 27 pivoted on said sleeves. The sleeves are mounted in bearings 28, 29, on side slides 30 connected by a cross-saddle 31 rigid therewith for forming 110

an upper feed roll frame. The sleeve 26 is rigidly secured to the slide, as by a set-screw 32, whereas the sleeve 25 forms the hub of a gear-cover 33 hereinafter more fully described.

The side-slides 30 of the upper feed-roll frame are long slides slidable up and down in long guideways 34 in recesses 35 at the outside of the sides of the main frame, 10 closed by outer plates 36 releasably held in place, as by screws 37, for ready access to said slides and the adjusting screws and nuts therefor.

The forming of the guideways for the upper feed-roll frame upon the outside faces 15 of the main frame of the machine permits the sides of the main frame to be cast integral with each other, in other words, permits an integral main frame to be formed, 20 by placing the parts thereof to be machined upon the outside of the main frame, and the provision of the covering plates for said recess forms pockets in which the slides of the feed-roll frame are adjustable, this construction removing the moving parts from 25 danger of contact with foreign substances.

The adjustment of the feed-roll frame is accomplished by means of screw-rod 38 journaled in bearings 39 in the respective 30 ends of said feed-roll frame. A block 40 is removably mounted in bearings 41, 42, in each side of the main frame, the blocks being threaded as at 43 between said bearings for threaded connection with said respective screw-rods, forming removable nut-blocks, readily removable when said threads are worn. Each of these screw-rods has on it a worm-wheel 44 meshed by worms 45 on a cross-shaft 46 journaled in bearings 47 40 on the feed-roll frame and having a hand-wheel 48 thereon for turning the same.

The screw-rods are received in vertical recesses 49 in the side-slides of the feed-roll frame, the screw-rod, nut-lock and guideways at each side of said feed-roll frame being located in coincident vertical planes projected lengthwise of the machine, providing ease of adjustment.

At each end of each roll housing, there is 50 a stop 51 which engages with a lug 52 on the feed-roll frame for limiting the downward movement of the upper feed-roll with relation to the plane of the stock-supporting table, the adjustment of the feed-roll frame 55 raising or lowering the upper feed-rolls for different thicknesses of lumber to be planed, the feed-rolls exerting pressure upon the stock and yielding up and down to inequalities of the stock by having the feed-roll 60 housings swing about their pivots.

In order to adjust the respective ends of the upper feed-rolls with relation to each other on said housings, and to adjust the relative elevations of said respective upper 65 feed-rolls, I mount each end of the shaft 53

of each of said feed-rolls in a bearing 54 slidable in a guideway 55 in the swinging end of said housing. For limiting the upward movement of the bearing a hollow bolt 56 is provided, which is threaded in a 70 threaded hole 57 in the housing and arranged to impinge said bearing. A bolt 58 is received through the bore 59 of the hollow bolt and has threaded connection in the threaded socket 60 in said bearing, the head 61 of said bolt being received above and supported by the hollow bolt, the head limiting the downward movement of the bearing in adjusting said bearing. The hollow bolt forms the positioning means for elevation of 80 the bearing and the inner bolt forms the means for clamping the bearing upwardly against said positioning means, the bearing being suspended from said inner bolt. By these means each end of each of the upper feed-roll shafts is adjusted, whereby the contact line of the periphery of each of said upper feed-rolls is adjusted with relation to the level of the stock being fed, so that upon unequal wear of the peripheral surface of 85 either of the rolls, the feeding or contact line thereof may be leveled with relation to the other roll, or either of said feed-rolls bodily raised or lowered with relation to the other.

I have shown means for driving the upper as well as the lower feed-rolls for feeding the stock either forwardly or back. My improved feeding mechanism is especially applicable to planing, planing and matching, and flooring machines, in which it is desired to maintain high rates of feed. In machines of this character, it has been found desirable at times to remove a board which has been partly fed into the machine. I 100 accomplish this by novel means for reversing the feed.

65 represents the main drive-shaft journaled in bearings 66, the inner ones of which are located on a bracket 67 secured to the 110 main frame. The shaft 65 has pulleys 68, 69, 70, received thereabout. The pulley 68 is tight on said shaft, the pulley 69 is loose thereabout, and the pulley 70 is on a sleeve 71 loose about said shaft.

72 is a reversing shaft journaled in bearings 73 on said bracket. A gear 74 is fast on said reversing shaft and meshes with a gear 75 fast with said sleeve-pulley 70.

76 is a cross-shaft journaled in bearings 77 120 in the main frame. It has a gear 78 fast thereon.

79 is a gear fast on the shaft 65.

80 is a gear on the reversing shaft.

The gears 79 and 80 are in mesh with the 125 gear 78.

A belt 81 is arranged to pass about the pulleys 68, 69, 70, and arranged to coöperate with any of said pulleys, being shiftable laterally by means of a belt-shifter 82 on an 130

arm 83 which may also have a tightener pulley 84 thereon in line with said belt-shifter, so that said belt-shifter and tightener pulley may simultaneously act on said belt. The arm is pivoted by a bearing 85 about a shifter-rod 86 operated by a handle 87 or in other suitable manner. A pulley 88 is on the shaft 65 for transmitting feeding motion to a set of feed-rolls in the rear part 10 of the machine or in rear of the cutting agency or cutting agencies, by a suitable belt 89. When the belt 81 passes about the pulley 68, a direct feed is imparted to the feed-rolls by rotating the shaft 76 in the direction of the arrow *a*, the transmission of said shaft being through the shaft 65, the gear 79 and the gear 78, the gears 75, 74 and 80 rotating reversely in idle relation. When the belt passes about the loose pulley 69, the 20 feed-rolls are at rest. When the belt is caused to pass about the sleeve-pulley 70, rotation is imparted to the shaft 76 in a direction opposite to the direction of the arrow *a* through the gears 75, 74, 80 and 78, thereby 25 rotating the feed-rolls in reverse directions for reversely feeding the stock and drawing the same backwardly out of the machine. The gear 79, main drive-shaft 65, and the pulley 68 in the meantime rotate in reverse 30 directions in idle relation, except when the pulley 88 is employed, when the shaft 65 acts as a transmitting shaft.

My improved construction is such that the forward or reverse feeds for the feed-rolls are 35 imparted by a straight belt, and the changes in feeding relations are obtained by a single belt, which is preferably a straight belt, received about said pulleys and shiftable from one pulley to another, thereby economizing 40 in power. Each of the lower feed-rolls has a shaft 91 journaled at each end of the feed-roll in a bearing 92, slideable up and down in a guideway 93 in the main frame.

94 is a stirrup from which the bearing is 45 hung, as by a bolt 95, rotatable in a bearing 96 in the stirrup, and threaded into a threaded socket 97 in the upper part of said bearing, a set-screw 98 clamping said bolt 95 in adjusted positions.

50 101 is an adjusting screw, threaded at 102 into the lower end of said stirrup, and journaled in a bearing 103 in the main frame, and held against downward movement by a collar 104.

55 105 is a bevel-gear fast to the lower end of the adjusting screw. Cross-shafts 106 are journaled in bearings 107 of the main frame. One of these cross-shafts has means thereon for turning the same, as the squared 60 end 108 arranged to receive an adjusting crank. Turning of the stirrup is limited by contact with the wall 109 of the guideway 93. Each of the cross-shafts has bevel-gears 111 thereon meshing with the bevel-gears 105.

112 is a connecting shaft journaled in bearings 113 of the main frame, and having bevel-gears 114 thereon, these last-named bevel-gears meshing with the bevel-gears 105 at one side of the main frame. 70

The turning of the turning means adjusts all of the stirrups simultaneously for adjusting the lower feed-rolls simultaneously up or down. The adjustment of the respective roll-shaft bearings with relation 75

to said stirrups permits independent adjustment of each end of each of the lower feed-rolls for alining the same with relation to each other, and causing selective projection of the contact line of the periphery 80 of each of the lower feed-rolls above the plane of the table, or for alining said contact-lines of the lower rolls with relation to each other when worn. The construction affords a simple, strong and durable 85 means for supporting the lower feed-rolls.

Gears 124, 125, are fast on the shaft 76. A gear 126 is fast on the shaft of the lower feed-roll 18 and a gear 127 is fast on the shaft of the lower feed-roll 19, the gears 90

126, 127, meshing with the gear 124 for rotating said feed-rolls in similar directions. The shaft of the lower feed-roll 19 also has a gear 128 which is journaled loose thereon, but rotates in the same direction as said 95

shaft, preferably at the same speed. The gear 128 meshes with the gear 125 and forms one of the transmitting gears for the transmitting train of gearing for driving the upper feed-rolls. Mounting said gear 100 128 about said feed-roll shaft permits economy in the size of gears and provides a compact and substantial construction, and avoids the necessity of employing a train of gearing off-set with relation to said roll-shaft.

129 is a gear mounted on a stud 130, the gear 129 meshing with the gear 128 and with a gear 131 fast on a cross-shaft 123 journaled in the sleeves 25, 26, mounted 110 in the upper feed-roll frame.

Novel gear covering and link mechanism is provided for the transmitting gearing between the cross-shaft 76 and the cross-shaft 123. Thus the gear-cover 33 comprises an inner wall 135, an outer wall 136, and a connecting flange 137 between said walls, the connecting flange having an interruption 138 therein. This gear-cover has a bearing 139 about the cross-shaft 123 and bearings 140, 141, in which the respective ends of the stud 130 are journaled. A connecting rib 142 integral with said gear-cover connects the bearings 139, 140, and a strengthening yoke 143 integral with said gear-cover connects the bearings 140, 141. The outer wall of the gear-cover is shown removable and is secured to the flange by screws 144. A portion of the said yoke is formed on said outer wall and a portion on 115 120 125 130

the inner part of the gear-cover, the yoke portions being rigidly connected by similar screws 144. A gear-cover 147 is provided which comprises an inner wall 148, 5 an outer wall 149, and a connecting flange 150 between said walls, said flange having an interruption 151 therein which mates with the interruption 138. Cheeks 153 extend from the flange 150 so that the flanges 10 at the respective ends of said interruptions may overlap each other irrespective of the swinging relations of said gear-covers. There is further an arc-joint 152 between said gear-covers at said interruptions so as to avoid any detrimental space between said gear-covers irrespective of the swinging positions between the same.

The gear-cover 147 is provided with a bearing 155 journaled about the journal-end 20 156 of the bearing 92 for the shaft of the lower feed-roll 19. The said gear-cover further has a link 157 integral therewith and projecting from said bearing 155, the said link having a bearing 158 at its end journaled about the journal-end 159 of the bearing 140 in which the stud 130 is journaled, a portion of said link being formed as a rib on the wall of said gear-cover and a portion thereof protruding beyond said gear-cover and received within the gear-cover 147. The inner wall of the gear-cover 147 is provided with an elongated opening 160 received about the bearing 77 of the cross-shaft 76 to permit oscillation of said gear-cover with relation to said bearing. The outer wall of the gear-cover 147 is preferably removable and is secured to the flange of said gear-cover by means of screws 161.

The lower gear-cover is pivoted about the 40 axis of rotation of the lower feed-roll 19 and the upper gear-cover and link mechanism is pivoted about the axis of rotation of the cross-shaft 123. The stud 130 between the said gear-covers follows the movements 45 of said gear-covers for maintaining proper meshing of the gear 129 with the gears 128 and 131, the swinging end of the lower gear-cover accommodating itself to the movements of adjustment of said gear-covers and 50 having free oscillation about the gears covered thereby. The construction of the mechanism insures complete covering for said gears throughout the range of adjustment of the feed-rolls and forms substantial link mechanism between the gears.

Gears 165, 166, are fast on the cross-shaft 123. A gear 167 is fast on the shaft of the upper feed-roll 20 and meshes with the gear 165 and a gear 168 is fast on the shaft of the upper feed-roll 21 and meshes with the gear 166, the said gears on said shafts of said respective feed-rolls being preferably at opposite ends of said feed-rolls.

Novel means are also provided for applying pressure to the yielding upper feed-

roll housings. Each of the upper feed-roll housings is pressed downwardly by a coil-spring 171, shown as a helical spring, the said springs being in laterally off-set relation, their upper ends crossing each other. 70 Each of the springs is located between a cup 172 on a rod 173 and a standard 174 on the cross-saddle 31, the upper end of the spring being received in a cup 175 in said standard. The rod has a threaded upper end 176 passing slidably through a hole 177 in the standard, a nut 178 being received about said threaded end. The lower end of the rod is provided with trunnions 179 received in a trunnion-socket 181. The spring is diagonally positioned with relation to the housing and acts directly upon a part of the housing within the arc of swing of the axis of rotation of the feed-roll therein, the said arc being indicated by the broken line 182. It is of course understood that one or more of these yielding mechanisms may be employed. I have shown two of these springs and rods, one for each of the roll-housings, the same being located in laterally off-set relation, their 80 upper ends crossing each other, preferably outside said arc 182. The inner ends of said springs and rods are preferably within said arc and their outer ends outside said arc. 90

The yielding pressure means shown and described provides compactness of structure, permits the feed-rolls to be placed closely adjacent to each other, and equalizes the pressure of the rolls upon the stock 10) throughout a wide range of yield of said rolls. The removable half of the bearings 77 are held in place by bolts 183 threaded into the cross-grit 184 of the main frame. 95

Having thus fully described my invention, 105 what I claim as new and desire to secure by Letters Patent, is:

1. In a feeding device for wood-working machinery, the combination of a main frame having sides, a feed-roll frame having long 110 side slides extending up and down, a feed-roll on said last-named frame, the sides of said main frame being provided with long recesses extending up and down at their outer faces and forming guideways for said 115 side slides, an outer plate secured to one of said frames at each side of said main frame forming covers for said guideways, a bearing in each of said side slides, a drive-shaft journaled therein, said drive-shaft extending through said sides, side slides and outer plates, a gear on said drive-shaft outside of and adjacent to each of said outer plates, a feed-roll, and transmitting gearing between one of said gears and said feed-roll. 120

2. In a feeding device for wood-working machinery, the combination of a lower feed-roll, a bearing at each end thereof, guiding means for each of said bearings, a stirrup formed as an independent member for each 130

of said bearings, an adjusting screw between the upper wall of each of said stirrups and the bearing therefor for adjustably hanging said respective bearings from said stirrups and independently adjusting the same, a second adjusting screw for each of said stirrups, said last-named adjusting screws having operative connections with the lower ends of said stirrups respectively, and turning means having operative connections with both said last-named adjusting screws for simultaneously raising and lowering said stirrups.

3. In a feeding device for wood-working machinery, the combination of a pivoted feed-roll housing, a support therefor, a feed-roll rotatively mounted in said housing, and pressure means for said feed-roll comprising a coil spring, said pressure means having operative connection with said housing within the circle of the arc of swing of the axis of rotation of said feed-roll between the vertical planes parallel to the pivotal axis of said housing in which said pivotal axis and said axis of rotation are respectively located, and the line of said spring extending slantingly between said operative connection and said vertical plane in which said pivotal axis is located.

30 4. In a feeding device for wood-working machinery, the combination of a pivotal feed-roll housing, a support therefor, a feed-roll rotatively mounted in said housing, pressure means for said feed-roll comprising a coil spring and a thrust-joint between one end of said spring and said housing, said thrust-joint being between the vertical planes parallel to the axis of rotation of said feed-roll and the pivotal axis of said housing in which said axes are respectively located, said coil spring extending between said support and housing in a slanting line between said thrust-joint and the vertical plane parallel to said pivotal axis in which said pivotal axis is located.

35 5. In a feeding device for wood-working machinery, the combination of a pair of oppositely extending pivoted feed-roll housings, a feed-roll in each of said housings, and coil pressure springs respectively for said housings slantingly arranged with relation to each other, the inner ends of said springs being athwart of each other in the vertical plane parallel to the pivotal axes 40 of said housings in which said pivotal axes are located, and the operative connections of the outer ends of said springs with said housings being respectively within the circles of the arcs of swing of the respective axes of rotation of said respective feed-rolls.

45 6. In a feeding device for wood-working machinery, the combination of a pivoted feed-roll housing, a support therefor, a feed-roll rotatively mounted in said housing, and pressure means for said feed-roll comprising

ing a coil spring located slantingly between said support and said housing, the operative connection of said pressure means with said housing being within the circle of the arc of swing of the axis of rotation of said feed-roll between the vertical planes parallel to the pivotal axis of said housing in which said pivotal axis and said axis of rotation are respectively located, and the entire line of the longitudinal axis of said spring with in the limits of said spring lying between planes parallel with said spring and the pivotal axis of said housing respectively intersecting said pivotal axis and tangent to said circle.

70 7. In a feeding device for wood-working machinery, the combination of an upper feed-roll, means for adjusting said upper feed-roll up and down, driving means for said upper feed-roll comprising a driving gear, a driven gear operative for rotating said upper feed-roll, and an intermediate gear, and gear covers for said gears, said gear-covers respectively pivoted at their separated ends about the axes of rotation of said driving gear and said driven gear, said gear-covers at their adjacent ends being crossingly arranged and provided with a bearing about the axis of rotation of said intermediate gear for the support of said intermediate gear and the pivotal connection of said covers.

75 8. In a feeding device for wood-working machinery, the combination of an upper feed-roll, means for adjusting said upper feed-roll up and down, driving means for said upper feed-roll comprising a driving gear, a driven gear operative for rotating said upper feed-roll, and an intermediate gear, and covering means for said gears comprising a plurality of gear-covers, said gear-covers respectively pivoted at their separated ends about the axes of rotation of said driving gear and said driven gear, the adjacent ends of said gear-covers being crossingly arranged and provided with a bearing about the axis of rotation of said intermediate gear, said gear-covers having an arc-joint between them.

80 9. In a feeding device for wood-working machinery, the combination of a main frame, an upper feed-roll, a driven-gear for the latter, a gear on said main frame, an intermediate gear between said first-named gears, and a pair of gear-covers between and having pivotal connection about said first-named gear and said second-named gear, one of said gear-covers comprising an integral link-extension received within the other of said gear-covers, said link-extension and said other of said gear-covers having pivotal bearings about the axis of rotation of said intermediate gear.

85 10. In a feeding device for wood-working machinery, the combination of a main frame,

- an upper feed-roll, a driven-gear for the latter, a gear on said main frame, an intermediate gear between said first-named gears, and a pair of gear-covers between said first-named gear and said second-named gear, 5 one of said gear-covers comprising an integral link-extension received within the other of said gear-covers, said link-extension and said other of said gear-covers having pivotal bearings about the axis of rotation of said intermediate gear, said gear-covers having an arc-joint between them, and said arc-joint comprising lapping flanges.
11. In a feeding device for wood-working machinery, the combination of a main frame, an upper feed-roll, a driven-gear for the latter, a driving gear on said main frame, a pair of intermediate gears between said first-named gears, and a pair of gear-covers having pivot bearings about three of the axes of rotation of said gears, the bearings about one of said axes of rotation forming 15 articulating connection between said gear-covers.
12. In a feeding device for wood-working machinery, the combination of a main frame, an upper feed-roll, a driven-gear for the latter, a driving gear on said main frame, a pair of intermediate gears between said first-named gears, and a pair of gear-covers located about all of said gears and having pivot-bearings about three of the axes of rotation of said gears, the bearings about 20 one of said axes of rotation forming articulating connection between said gear-covers, the part of the gear-cover received about the remaining one of said gears being shiftable crosswise of the axis of rotation of the same.
13. In a feeding device for wood-working machinery, the combination of a main frame, an upper feed-roll, a driven-gear for the latter, a driving gear on said main frame, a pair of intermediate gears between 25 said first-named gears, and a pair of gear-covers having pivot-bearings about three of the axes of rotation of said gears, the bearings about one of said axis of rotation forming articulating connection between said gear-covers, the part of the gear-cover received about the remaining one of said gears being shiftable crosswise of the axis of rotation of the same.
14. In a feeding device for wood-working machinery, the combination of a main frame, an upper feed-roll, a driven-gear for the latter, a driving gear on said main frame, a pair of intermediate gears between 30 said first-named gears, and a pair of gear-covers comprising a link-extension rigid therewith received within the other of said gear-covers, said extension having one of said pivot-bearings thereon.
15. In a feeding device for wood-working machinery, the combination of a main frame, an upper feed-roll, a driven-gear for the latter, a driving gear on said main frame, a pair of intermediate gears between 35 said first-named gears, and a pair of gear-covers comprising flanges and outer plates received about all said gears, said gear-covers having pivot-bearings about three of the axes of rotation of said gears, the bearings about one of said axes of rotation forming articulating connection between said gear-covers, the part of the gear-cover received about the remaining one of said gears being shiftable crosswise of the axis of rotation of the same.
16. In a feeding device for wood-working machinery, the combination of a main frame, an upper feed-roll frame, a feed-roll thereon, a drive-shaft therefor journaled in said feed-roll frame, a gear on each of said drive-shafts, a pair of intermediate gears, a pair of gear-covers, one of said gear-covers having a pivot-bearing coincident with the axis of rotation of said second-named drive-shaft, the other of said gear-covers having a pivot-bearing about the axis of rotation of one of said intermediate gears, and said gear-covers articulated together about the axis of rotation of the other of said intermediate gears, said gear-covers comprising plates at the outside of said gears.
17. In a feeding device for wood-working machinery, the combination of a main frame, a lower feed-roll journaled therein, an upper feed-roll frame, an upper feed-roll thereon, a gear on said feed-roll frame for driving said upper feed-roll, and a gear loose about the axis of rotation of said lower feed-roll for driving said last-named gear.
18. In a feeding device for wood-working machinery, the combination of a main frame, an upper feed-roll frame adjustable thereon, a feed-roll housing, an upper feed-roll therein, a drive-shaft therefor on said feed-roll frame, a gear on said drive-shaft, an intermediate gear for driving the same, a pivoted gear-cover about said gears, said gear-cover having a pivot-hub about said drive-shaft, a bearing on said feed-roll frame for said hub, and a bearing for said 115 housing on said hub, substantially as described.
19. In a feeding device for wood-working machinery, the combination of a drive-shaft, feed-rolls, driving means between said drive- 120

shaft and feed-rolls, a driving gear on said drive-shaft, a pair of driving pinions in operative engagement with said gear, a pair of shafts to which said pinions are respectively secured, three pulleys whose axes of rotation are coincident with the axis of rotation of one of said pair of shafts, one of said pulleys fast on said last-named shaft, another of said pulleys loose about said last-named shaft, and a sleeve loose about said last-named shaft to which the third of said pulleys is secured, a gear fast on said sleeve,

and a gear in operative engagement with said last-named gear fast on the other shaft of said pair of shafts, for the purpose described. 15

In testimony whereof, I have hereunto signed my name in the presence of two subscribing witnesses.

PETER A. SOLEM.

Witnesses:

CHARLES E. WEBER,
THERESA SILBER.
